UNITED STATES PATENT OFFICE.

STEPHEN WILCOX, OF BROOKLYN, NEW YORK.

COMPOUND ENGINE.

SPECIFICATION forming part of Letters Patent No. 445,386, dated January 27, 1891.

Application filed June 28, 1890. Serial No. 357,065. (No model.)

To all whom it may concern:

Be it known that I, STEPHEN WILCOX, a citizen of the United States, residing at the city of Brooklyn, county of Kings, and State 5 of New York, have invented certain new and useful Improvements in Compound Steam-Engines, of which the following is a specification, reference being had to the accompanying drawings, in which similar numerals of reference indicate corresponding parts throughout, and in which—

Figure 1 is a general front elevation; Fig. 2, a plan view; Fig. 3, a sectional elevation taken on the line x x ; Figs. 2 and 4; Fig. 4, a 15 horizontal section taken on the line x' x' ; Fig. 3; Fig. 5, a vertical sectional elevation taken at right angles to Fig. 3 on the line x^2 x^2 thereof, looking in the direction indicated by arrows; Fig. 6, a detail view showing in vertical section on the line x^3 x^3 , Fig. 3, one of the low-pressure cylinders, the piston being removed; and Fig. 7, a detail view representing the steam chest and valves of the high-pressure cylinder as they would appear taken 20 in section on the line x^4 x^4 , Fig. 4.

This invention relates to compound engines for either land or marine purposes; and it consists in the embodiment in a triple or other expansion engine of a series of single-30 acting low-pressure cylinders axially aligned with the double-acting high-pressure cylinders and having connected pistons which are connected to a single crank upon the driving-shaft, the steam distributed to the series of 35 cylinders in alignment being governed by the same valve-gear.

I have illustrated herewith a triple-expansion engine as one appropriate embodiment of my invention, and of which 1 represents 40 the high-pressure cylinder, 2 the intermediate cylinder, and 3 3' two single-acting cylinders sharing equally the function of a third or low-pressure cylinder. The vertical space occupied by the low-pressure cylinders 3 3' is 45 substantially equal to that usually occupied by the cross-heads and guides, the aggregate height of the engine being thus normal or corresponding to that of the ordinary construction referred to, while such amount of 50 horizontal or shaft length of the engine as corresponds to the diameter of the low-pressure cylinder, combined with the receiving-

chamber from whence its steam is supplied, when located on a common level with the other cylinders, is dispensed with, rendering 55 the engine very compact and self-contained. The eccentrics 11 12 are each controlled by a governor 13, the same having any construction such as that well known to the art, and not requiring detailed description here. 60

The cylinders 3 3' compose a part of the frame of the machine, supporting the cylinders 1 2 above them. By this feature of location of the cylinders 3 3' the center of gravity of the structure as a whole is lowered and 65 an increased length of the connecting-rods 20 permitted without rendering the engine top-heavy. The upper cylinders 1 2 are supported solely by the necks 14 fitting the flanges 16 of the low-pressure cylinders, (and 70 the cylinders 1 2 are also braced partially by the branched pipe 15;) but such upper cylinders 1 2 may be additionally supported by suitable frames or braces in situations where necessary. 75

The frame 4 and its base 5 supporting the machine is of course susceptible of various construction, according to circumstances of situation, whether upon a stationary foundation or within a marine vessel. An inclosed 80 or box form of supporting-frame is herewith illustrated as one form of construction suitable to a stationary engine.

The shaft 6 is supported in bearings 7 in the base 5, and the cranks 8 8' are fixed at 85 the usual angle of ninety degrees with reference to one another about the axis of the shaft.

The pistons 21 22 of each of the upper and lower cylinders, respectively, are connected 90 by piston-rods 23 passing through suitable packings 24 in the supporting-necks 14, and the bearing-surfaces of the single-acting pistons 22 are elongated sufficiently to afford a proper resisting wear against the side-thrust 95 of the connecting-rods 20, connected thereto.

25 26 are balanced piston-valves for the high-pressure cylinders 1 and 2, respectively, the induction side being between such pistons and the eduction at the opposite or exterior ends thereof, the reciprocation of each being imparted by the respective eccentrics 11 12 and their rods 28, through sliding bars 27. The piston-valve 26 is employed in du-

pliate, as seen in plain view in Fig. 4, for the purpose of duly enlarging the capacity thereof, and the two valve-stems are connected by a yoke 35, Fig. 3, upon the upper end 5 of the slide 27, thereby operating in unison.

30 are the induction and 31 the eduction valves of the "Corliss" type for the low-pressure cylinders 3 3', both operated from wrist-plates 32, common to each, which wrist-plates 10 are also driven by the eccentrics 11 12 through the rods 28 of the latter and the connecting-rods 33.

The combined receiving-chambers 9 10, the structure whereof unites the upper part of 15 the machine, includes two separators 40 41 for eliminating condensed portions of steam during its transmission from one to another of the successive cylinders, suitable drip or discharge valves being provided for removing 20 the accumulated water in the wells of the separators. I concentrate the receiving-chambers 9 and 10, Fig. 4, of the primary and intermediate cylinders 1 2, respectively, into one structure, separating the said cylinders 25 only sufficiently to leave convenient space for also concentrating all the parts of the valve-gear below such chambers 9 10, and between the cylinders.

The arrangement of the receivers, separators, valves, and valve-gear herein referred to whereby the particular space is utilized to contain these parts and the structure thereby rendered more compact is not of my invention, and I hereby disclaim the same, such 35 subject-matter being the invention of August A. Goubert, and is claimed by him in an application for a patent filed simultaneously herewith. I will, however, herein describe, briefly, the structure of the receivers and the 40 course of the steam therein sufficiently to make clear the co-operative relation between the other parts of the machine forming the subject of my invention.

50 is the initial-pressure steam-pipe connecting to the induction-side 60 of the valve 25, the steam being distributed to the cylinder 1 through the ports 52. The partly-expanded steam from the cylinder 1, issuing from the eduction sides of the valve 25, is delivered 45 through the passages 53 to the opening 54 of the first separator 40, the current from the lower passage 53 passing upward through the conduit 55. The current of steam thence enters tangentially the space between the inner and outer concentric pipes of the separator 40, being directed by the inclined bridge 56, Fig. 3, following a spiral downward course, the water separating centrifugally. The dry- 55 steam current then returns upwardly through 60 the inner concentric pipe, and is transferred through the goose-necked pipe 57 into the first receiving-chamber 9. From the receiving-chamber 9 the steam is then admitted to the induction side 60' of the valves 26 and distributed to the ports 59 of the intermediate cylinder 2, the connecting-passage 58, Fig. 65 3, effecting communication in the direction

indicated by the arrow 58' in Fig. 4. The further expanded steam delivered from the eduction sides of the valves 26, through the 70 passages 61, is conducted to the common opening 62, the current from the lower passage 61 passing upward through the conduit 63. The current of steam is thence admitted tangentially between the inner and outer concentric pipes of the separator 41, as before described with reference to the first separator, a downward spiral course being followed and a subsequent upper course through the inner concentric pipe and goose-necked pipe 64 80 delivers the steam into the second receiving-chamber 10. From the receiving-chamber 10 the steam is conducted through the bifurcated pipe 15 and distributed to the two single-acting cylinders 3 3' by the induction-valves 30, 85 and subsequently exhausted through the eduction-valves 31 to the condenser or atmosphere.

70 are automatic relief-valves (see Fig. 7) capable of opening toward the pressure on the 90 induction side of the cylinder-valves to relieve the pressure of cushioning-compression when the same exceeds the initial pressure such as contained on said induction side. The valves 70 are of the check-valve type, 95 seated against openings from the ports 52 or 59, and discharge the steam into the steam-chamber 60 instead of a waste-passage, (said valves being applied to both cylinders 1 and 2,) and to the above purposes they control 100 communication of said ports with the steam-chests 60 or 60'. The valves 70 are retained upon their seats by suitable springs, such as usual to check-valves, and they are thereby retained in a closed position before pressure 105 is applied in starting the engine.

In the operation of my invention the two single-acting low-pressure cylinders share equally the expanded steam from the receiver 10 of the intermediate cylinder and co-operate with the same motive effect as would be derived from one double-acting low-pressure cylinder located in the usual lateral conjunction with the other cylinders. In order to counteract the effect of the impulses of the 115 low-pressure cylinders that are concentrated in the downward stroke, a greater degree of cushioning-compression may be employed in the lower ends than in the upper ends of the cylinders 1 2 by a proper adjustment of the valves. The cranks 8' are not, however, essentially placed at a right angle to one another about the axis of the shaft. They may be placed at a half-circle apart, or substantially opposite, as commonly practiced heretofore in 125 compound engines, distributing the said impulses at equal intervals in the rotation of the shaft.

Having thus fully described my invention, what I claim, and desire to secure by Letters 130 Patent, is—

1. A compound engine having an intermediate receiver, consisting of a double-acting high-pressure cylinder and a single-acting

low-pressure cylinder located adjacent to and in alignment with said high-pressure cylinder, and having connected pistons which are connected to a single crank, and provided with a 5 single valve-gear that governs the distribution of steam in the respective cylinders, substantially in the manner described.

2. The combination, in a compound receiver-engine, of two or more double-acting cylinders located in lateral relation, single-acting cylinders arranged in common axial alignment severally therewith, provided with connected pistons within the commonly-aligned cylinders, their shaft crank connecting rods 15 being severally pivoted upon and guided by the single-acting pistons, and a valve-gearing that governs the distribution of steam in said commonly-aligned cylinders.

3. The combination, in a compound receiver-engine, of a double-acting high-pressure and intermediate cylinder located in lateral relation, single-acting low-pressure cylinders severally located in common axial alignment with said high and intermediate pressure 20 cylinders, connected pistons in the aligned cylinders, and steam-distributing valves and successive passages for the same, delivering the steam first to the said double-acting cylinders in series consecutively and then to the 25 30 distributing-valves of the single-acting cylinders,

ders, the respective supply-passages of the latter being connected in common.

4. The combination, in a compound engine, of a double-acting high-pressure cylinder and receiver, a double-acting intermediate cylinder and receiver located in lateral relation to the high-pressure cylinder, and single-acting low-pressure cylinders severally aligned with the said high and intermediate pressure cylinders, having pistons connected in common therewith, as described, and having the induction side of their distributing-valves connected in common with the final receiver of the said double-acting cylinders. 35 40

5. The combination, in a compound receiver-engine, of a double-acting high-pressure and intermediate cylinder located in lateral relation, single-acting low-pressure cylinders axially aligned therewith, connected pistons in the aligned cylinders, reciprocating steam-distributing valves for the double-acting cylinders, and rock-motion distributing-valves for the single-acting cylinders, together with connecting valve-gearing for operating all the 45 50 valves of the respective aligned cylinders.

STEPHEN WILCOX.
